BROOM

Admiral J. Warren, Washington, D. C.

Application February 10, 1933. Serial No. 656,156

6 Claims. (Cl. 306—20)

This invention relates to floor sweeping brushes or floor brooms, the primary object of the invention being to provide a device of this character including novel means for securing the handle 5 to the head of the brush or broom.

An important object of the invention is to provide a handle socket member embodying a length of wire material formed into a series of connected loops, of a diameter to accommodate one 10 end of the handle, one end of the wire extending through the socket, and passed into a concentric opening formed in the end of the handle, to the end that a binding action is set up between the handle and socket member, securely holding the 15 handle within the socket member.

Another object of the invention is to provide a connection of this character which will yield when the broom is in operation, and when the broom head is being knocked against a stationary 20 object to remove the dirt or dust therefrom, thereby insuring against the handle breaking, at its point of connection with the broom head.

With the foregoing and other objects in view, which will appear as the description proceeds, 25 the invention resides in the combination and arrangement of parts and in the details of construction hereinafter described and claimed, it being understood that changes in the precise embodiment of the invention herein disclosed 30 may be made within the scope of what is claimed, without departing from the spirit of the invention.

Referring to the drawing:

Figure 1 is a fragmental plan view of a brush 35 equipped with a handle socket constructed in accordance with the invention.

Figure 2 is a fragmental plan view of a broom showing a socket member, and illustrating the 40 position of the pin of the socket member, prior to positioning the handle.

Figure 3 is a vertical sectional view through the head of the brush.

Figure 4 is a longitudinal sectional view 45 through the tapered end of the handle, used with the socket member.

Referring to the drawing in detail, the head of a brush is indicated by the reference character 5, and as shown, the brush head is formed with a cut out portion 6 extending transversely thereof at a point intermediate the ends of the brush head.

This cut out portion 6, is designed to accommodate the extension 7 of the handle socket member indicated generally by the reference character 55 8, the extension 7 being in the form of a loop

provided with parallel leg members 9, spaced apart in such a way that the extension 7 will contact with the walls of the cut out portion 6.

The reference character 10 designates a bolt that is secured to the head 5 and extended through the brush head, at a point intermediate the ends of the cut out portion 6, as clearly shown by the drawing.

Positioned on the bolt 10, is a washer indicated at 11, which is engaged by the winged nut 12, that operates on the bolt, the washer being forced into engagement with the extension 7, by means of the winged nut, thereby securely holding the socket member 8, on the head 5.

Thus it will be seen that due to this construction, the socket member may be adjusted longitudinally of the cut out portion, and since the extension 7 and brush head 5 are curved, it will be seen that by making this adjustment, the handle may be moved to various angles with respect to the head, for the convenience of the operator.

It will be seen that by this adjustment, the brush head may be held at any desired angle.

In the formation of the handle socket member, 80 a length of wire is used, the length of wire being formed into a series of connected loops 13, the diameters of the loops being reduced in size, towards the extension 7, so that a tapered socket is provided to receive the tapered end of the broom handle indicated at 14.

The extension 7 forms a continuation of the length of wire of which the socket member is constructed, and the free end of the extension is extended upwardly through the socket member, 90 as clearly shown by the drawing, providing a pin 15 to be extended into a concentrically formed opening, disposed at the end of the handle 14.

The pin 15 is eccentrically disposed within the socket member, so that when the handle 14 is positioned within the socket member and the pin 15 extended into the concentric opening of the handle, the pin 15 will be bent towards the center of the socket member, with the result that a binding action is set up between the handle and socket member, due to the lateral pressure of the pin within the concentric opening of the handle.

The loops of which the socket member is formed, also provide what might be termed 105 threads, adapted to bite into the wooden handle, to better secure the handle within the socket member.

It will also be seen that the construction of the socket member will yield, while the broom 110 is in operation, or when the broom head is being

struck against a stationary object in cleaning the broom head, thereby insuring against the handle becoming broken, while in use.

Having thus described the invention what is claimed is:

1. A broom comprising a head member and a handle member, a socket member secured to the head member, a yieldable pin disposed eccentrically within the socket member, said handle member having a concentric bore formed in one end thereof, said handle adapted to fit within the socket member, and said pin extending into the bore setting up a binding action with the wall of the bore securing the handle within the socket member.

2. A broom comprising a head and handle, a socket member including a plurality of connected loops varying in diameter towards the lower end of the socket member, a yieldable pin extending through the socket member and disposed laterally of the axis of the socket member, said handle having a bore to accommodate the pin, and said pin setting up a binding action with the wall of the bore of the handle securing the handle within the socket member.

3. A broom comprising a head and a handle, a socket member secured to the head, said socket member comprising a length of wire formed into a plurality of superposed loops, one end of the length of wire extending laterally from the socket member providing a loop, from where the end of the wire extends through the socket member, and said handle being fitted in the socket member having an opening to receive the extremity of

the wire extending through the socket member, and means on the head and engaging the laterally extended portion of the wire, securing the socket member to the head.

4. A broom comprising a head and handle, a socket member mounted on the head, a pin extending through the socket member and disposed eccentrically therein, said handle having a bore disposed centrally in one end thereof, said bore accommodating the pin when the handle is forced into the socket member, securing the handle within the socket member.

5. A broom comprising in combination a head member and a handle member, one of the members having a socket, a laterally yieldable pin extending into the socket, the other member being fitted in the socket and having an opening disposed centrally thereof to accommodate the pin, said pin being normally disposed laterally of the opening setting up a binding action by its contact with the wall of the opening, securing the head member and handle member together.

6. A broom comprising a head and a handle, a socket member adjustably secured to the head, a pin forming a part of the socket member and extending into the socket member at the base thereof, the free end of the pin being disposed near the wall of the socket member, said handle having a central bore formed in one end thereof, said bore accommodating the pin setting up a binding action between the wall of the bore and pin, securing the handle in the socket.
